DESIGN FOR A WRAPPING PAPER

Grace Chess Robinson, New York, N. Y.

Application May 4, 1940, Serial No. 92,171

Term of patent 14 years

To all whom it may concern:

Be it known that I, Grace Chess Robinson, a citizen of the United States, residing in the Borough of Manhattan, county, city, and State of New York, have invented a new, original, and ornamental Design for Wrapping Paper, of which the following is a specification, reference being had to the accompanying drawing, forming a part thereof.

The drawing shows a fragmentary view of a piece of wrapping paper showing the new design.

The feature of novelty resides in the alternate arrangement of the ornamental and solid squares as shown.

I claim:

The ornamental design for wrapping paper, as shown and described.

GRACE CHESS ROBINSON.
